(57) **CLAIM**

The ornamental design for a computer mirror, as shown and described.

DESCRIPTION

FIG. 1 is a perspective view of a computer mirror embodying my new design wherein a computer unit is shown in broken lines for illustrative purposes only and forms no part of the claimed design;

FIG. 2 is a front elevational view thereof;

FIG. 3 is a rear elevational view thereof;

FIG. 4 is a top view thereof;

FIG. 5 is a bottom view thereof;

FIG. 6 is a left end view thereof; and,

FIG. 7 is a right view thereof.
